CLAIM

The ornamental design for a separable tetrahedral icosahedron block, as shown and described.

DESCRIPTION

FIG. 1 is a first perspective view of the separable tetrahedral icosahedron block, showing my new design;

FIG. 2 is a second perspective view thereof;

FIG. 3 is a third perspective view thereof;

FIG. 4 is a fourth perspective view thereof;

FIG. 5 is a first perspective view of the separable tetrahedral icosahedron block, showing my new design;

FIG. 6 is a second perspective view thereof;

FIG. 7 is a third perspective view thereof; and,

FIG. 8 is a fourth perspective view thereof.

1 Claim, 8 Drawing Sheets
